UNITED STATES PATENT OFFICE.

GEORGE ASHWORTH AND ELIJAH ASHWORTH, OF MANCHESTER, COUNTY OF LANCASTER, ENGLAND.

CARDING-MACHINE.

SPECIFICATION forming part of Letters Patent No. 321,331, dated June 30, 1885.

Application filed November 28, 1883. (No model.) Patented in England May 15, 1883, No. 2,432; in France November 20, 1883, No. 158,678; in Belgium December 27, 1883, No. 62,671, and in Germany January 11, 1884, No. 28,029.

To all whom it may concern:

Be it known that we, GEORGE ASHWORTH and ELIJAH ASHWORTH, subjects of the Queen of Great Britain and Ireland, and residing at 5 Manchester, county of Lancaster, England, have invented an Improvement in Carding-Machines, (for which we obtained a patent in Great Britain, No. 2,432, dated May 15, 1883,) of which the following is a specification.

10 Our invention consists of certain improvements in the construction of carding-machines, in which the main cylinder is provided with end plates or disks to assist in producing a fleece of fibrous material with straight and 15 regular edges, as fully described and claimed hereinafter.

In the accompanying drawings, Figure 1 is an end view of a carding-engine cylinder with our invention applied thereto. Fig. 2 is a 20 sectional view of one end of the cylinder with the removable disk applied thereto. Figs. 3 and 4 are detached views, on a larger scale, of the appliances for fixing the disk or ring when it has been detached from the cylinder. Fig. 25 5 is a diagram illustrating the position of the disk or ring during the grinding of the cylinder-clothing.

In Fig. 2, *a* is one end of the main cylinder of a carding-engine. *b* is the central shaft or 30 axle, and *c* is the disk or ring which we apply to the cylinder. The end of the cylinder is turned true, and the disk *c* is secured to the cylinder end by means of screws *d*. The disk is, by preference, made of sheet-steel. The 35 card-clothing extends right up to this disk, and the "licker-in," the "doffer," and the "flats" or rollers just enter between the peripheries of the two disks, which project a little beyond the wires of the clothing at the 40 ends of the cylinder, so that the whole of the width between these disks is evenly covered with cotton, which is carded right up to the disks. The two disks thus limit the width of the carding-surface, and prevent the cotton 45 from spreading sidewise. In each disk two key-hole-shaped slots, *e e*, are cut. When the cylinder is to be ground, two holders similar to the one represented in Fig. 3 are secured to the disk. This holder consists of a screw, 50 *f*, which is formed with a head, *f'*, which can

pass through the enlarged end of the slot *e*. In this head is turned a groove about equal in width to the thickness of the disk. The screw is provided with a conveniently-shaped tapped handle, *g*, or with an ordinary nut, or 55 with any suitably-shaped nut or screw handle. When the head of the screw is entered into the circular hole at one end of the slot *e*, and is pushed sidewise along the slot, the holder is secured to the disk by the edges 60 of the slot passing into the groove in the head of the bolt. This being done in the case of both slots in both the disks, the screws *d* are removed, the disks being then sustained by the resting of the holders upon brackets *h h*, which 65 are secured to the ordinary framing, *i*, of the carding-engine. In each bracket *h* is formed a notch, *h'*. When the two holders are moved sidewise, the part of the screw between the head *f'* and the boss of the handle *g* drops into 70 this notch, as indicated in Fig. 4, and the two handles are turned, so as to tighten up the screws. The disk is then firmly held in a position eccentric with relation to the axis of the cylinder, as shown at Fig. 5, and the tightening of the screws has withdrawn the disks a little from the cylinder, so that the latter 75 can run clear of the disk on each side. The wires of the card-clothing will now project at one part beyond the peripheries of the disk, as 80 indicated in Fig. 5, and a grinding-roller can be applied to grind the carding-surface. The disk *c* may have a larger hole in the center than the proportion as indicated in the drawings, so as to be more in the nature of a ring, 85 and instead of being a complete disk or ring, as indicated, it may be applied in separate segments.

We are aware of the construction proposed in British Patent No. 2,519, of 1862, "to prevent the fibrous material from passing sideways" from the carding-cylinder; but in that case the rings are fixedly applied to the peripheries of the cylinders, are of the same diameter as the clothed cylinder, and are 95 "ground away when the cylinders require sharpening."

We claim as our invention—

1. The combination of the cylinder and the frame of a carding-engine, having supporting-

brackets, with a metal disk, means, substantially as described, for detachably securing the disk to one end of the cylinder, and handles for said disk, as set forth.

- 5 2. The combination of the frame of a carding-engine, having brackets *h h*, provided with notches *h'*, with the main cylinder, a disk, *c*, adapted to be detachably secured to the end of the cylinder, and having slots *e*, and screw-holders *f g*, for sustaining the disk in an eccentric position with relation to the cylinder dur-

ing the grinding of the carding-surface, substantially as set forth.

In testimony whereof we have signed our names to this specification in the presence of 15 two subscribing witnesses.

GEO. ASHWORTH.
ELIJAH ASHWORTH.
